UNITED STATES PATENT OFFICE.

OSCAR C. STAPLES, OF TULSA, OKLAHOMA.

SAFETY CONNECTING LINK.

Application filed June 28, 1926, Serial No. 118,970

This invention relates to new and useful improvements in safety connecting links.

The invention has particularly to do with the links which are used to connect the rods extending from pumping powers to pump jacks as used in the oil fields, and is an improvement on the invention set forth in my Letters Patent #1,561,952, issued November 17, 1925.

10 The object of the invention is to provide a hook having an eye at one end whereby it may be permanently connected to the jack rod and a hook at the other end for connecting with the power rod, together with a hand grip located intermediate its ends for safely handling the link.

Another important object of the invention is to provide a guard adjacent the hand grip and opposite the connecting hook for preventing injury to the operator's hand by contact with the rod.

Another object of the invention is to provide certain reinforcements and thus preclude breakage and distortion, which is quite common with the links now in general use.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a view in elevation showing a link constructed in accordance with my invention, and connecting a pumping rod with a jack rod,

Fig. 2 is a side elevation of the said link,

Fig. 3 is a cross-sectional view taken on the line 3—3 of Fig. 2, and

Fig. 4 is a cross-sectional view taken on the line 4—4 of Fig. 2.

In the drawings the numeral 10 designates a metal connecting link which may be cast, forged or otherwise formed from suitable metal. At one end the link is formed with an eye 11. The eye is surrounded by a ring 12 which is merged into a longitudinal shank 13. The shank is merged into a neck portion 14. A curved hand grip 15 is arched over the shank from the ring 12 to the neck 14 into which it is merged at its ends. This provides an elliptical open-

ing 16 between the shank and the grip extending longitudinal of the link.

A reinforcing fin 17 extends upwardly from the grip 15 and terminates in a guard lug 18 projecting outwardly at the forward end of the grip. The front side of the lug is curved downward to the neck 14. A connecting hook 19 is provided at the outer end of the neck while a throw-off hook 20 is curved downwardly from the inner end of the neck so as to underlie the shank. A reinforcing web 21 connects the hooks and extends across the outer end of the neck.

In using the hook the eye 11 is attached to the coupling A of the pump jack rod B. The operator grasps the link by the hand grip 15, passing his fingers through the opening 16 and placing his thumb against the guard lug 18. With the link thus held and his hand and thumb protected, he places the disconnecting block (not shown) between the coupling A and the knock-off post E. The link will then drop off in the usual way. To connect the link the operator grasps the hand grip 15 with one hand and engages the hook 19 in the coupling C of the power rod D.

Where the link is used with an anchor or a hook-off the operator grasps the grip 15 and engages the hook 20 in the clamp of the hook-off rod (not shown), whereby the hook 19 will disengage on the return reciprocation of the rod D and drop off. When the hook 19 is engaged with the coupling C the hook-off rod will drop off the hook 20.

It will be seen that the lug 18 will prevent injury to the operator's hand by engaging the coupling C in case the rod B moves forwardly to this point. The web 21 gives the hook structure sufficient strength and yet reduces the weight to a minimum.

Various changes in the size and shape of the different parts, as well as modifications and alterations, may be made within the scope of the appended claims.

What I claim, is:

1. A safety connecting link for pump rods, comprising, a link body having a connecting eye at one end and a coupling hook at its opposite end, and a hand grip between the eye and the hook, there being a finger opening under the hand grip.

2. A safety connecting link for pump rods comprising, a link body having a connecting eye at one end and a coupling hook at its opposite end, a hand grip between the eye and the hook, there being a finger opening under the hand grip, and a guard lug at the hook end of the hand grip.
3. A safety connecting link for pumping rods comprising, a longitudinal shank having a ring with an eye at one end and a connecting hook at the other end, a hand grip arched over the shank and providing a finger opening therebetween, and a guard lug at the hook end of the hand grip.
4. A safety connecting link for pumping rods comprising, a longitudinal shank having a ring with an eye at one end and a connecting hook at the other end, a hand grip arched over the shank and providing a finger opening therebetween, a guard lug at the hook end of the hand grip, and a rein-

forcing fin extending along the outer side of the hand grip and merged into the guard lug.

5. A safety connecting link for pumping rods comprising, a longitudinal shank having a ring with an eye at one end and a neck at its opposite end, a connecting hook at the outer end of the neck, a throw-off hook at the inner end of the neck, a reinforcing web extending outwardly from the neck and connecting the hooks, a curved hand grip arched over the shank and providing a finger opening therebetween, a guard lug extending outwardly from the grip and curved downwardly to the neck, and a reinforcing fin extending along the grip and merged into the lug.

In testimony whereof I affix my signature.

OSCAR C. STAPLES.
